UNITED STATES PATENT OFFICE.

ROSE THAMM, OF BERKELEY, CALIFORNIA.

DESIGN FOR A GARMENT-HANGER.

45,437.

Specification for Design.

Patented Mar. 17, 1914.

Application filed December 15, 1913. Serial No. 806,944. Term of patent 3½ years.

To all whom it may concern:

Be it known that I, ROSE THAMM, a citizen of the United States, residing at Berkeley, in the county of Alameda and State of California, have invented a new, original, and ornamental Design for Garment-Hangers, of which the following is a specification, reference being had to the accompanying drawing, forming part thereof.

The figure is a perspective view of a garment hanger, showing my new design.

I claim:

The ornamental design for a garment hanger, substantially as shown.

ROSE THAMM.

Witnesses:

M. C. BLUM,
F. J. STARK.
